(57) **CLAIM**

We claim the ornamental design for a device for installing a screen protector, as shown and described.

DESCRIPTION

FIG. 1 is a front view of a device for installing a screen protector showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, right and bottom perspective view thereof; and,

FIG. 8 is a rear, left and bottom perspective view thereof.

1 Claim, 8 Drawing Sheets
